HENRY C. KELLER, OF SYRACUSE, NEW YORK, AND MAYNARD VAN BILLIARD, OF PHILADELPHIA, PENNSYLVANIA, ASSIGNEES TO THE LAMSON COMPANY, OF SYRACUSE, NEW YORK, A CORPORATION OF MASSACHUSETTS

CONVEYER

Application filed April 22, 1930. Serial No. 446,231.

This invention relates to an improvement in conveyers and more particularly to the provision of means for delivering to a main conveyer a plurality of load units supplied 5 by several branch conveyers.

The primary object of the invention is to provide means which insures that the load units delivered to the main conveyer by each branch conveyer are spaced a predetermined 10 distance apart to permit the delivery to the main conveyer of load units from other branch conveyers without danger of collision. A further object of the invention is to provide means associated with each branch 15 conveyer for stopping at regular intervals the travel of the load units fed thereby, such means being controlled by mechanism so that they function alternatively, whereby the load unit on one branch conveyer only travels and 20 the unit on the other branch conveyers are at rest.

Another object of the invention is to provide a conveyer comprising two article transporting sections and a movable section interposed between the first two which section in 25 one position receives a predetermined load unit from one section and in another position delivers such load unit to the other section in combination with a stop associated with the 30 movable section and movable relative thereto and means for actuating the movable section and stop. Other objects of the invention will appear from an examination of the following specification and of the drawings 35 which form a part thereof wherein one embodiment of this invention is set forth for purpose of illustration.

The embodiment of the invention selected 40 for illustration comprises two branch conveyers by which boxes are delivered to a main conveyer, but it will be understood that the number of branch conveyers may be changed and that the illustrated embodiment 45 may be altered in various respects without departing from the spirit and scope of the invention as hereinafter described.

In the drawings:

Fig. 1 is a plan view of such embodiment; 50 Fig. 2 is a side elevation of one of the

branch conveyers taken along the line 2—2 of Fig. 1; and

Figs. 3 and 4 are side elevations of certain elements of one of the branch conveyers, said elements being shown in Fig. 3 with the load 55 units at rest, and in Fig. 4 with one load unit free to travel.

This invention embodies broadly a main conveyer A and a pair of branch conveyers B and C by which boxes are delivered to the 60 main conveyer. The conveyer A may be of any desired type and is here shown as a belt conveyer which travels in either direction as indicated by the double-headed arrow on Fig. 1. The belt 10 of the selected main conveyer passes over a plurality of rollers 11 in the usual manner and is driven by a motor or other suitable source of supply (not shown). Side walls 12 and 13 are provided between which the conveyer belt 10 passes. 65 The side wall 12 comprises a suitably supported angle bar on the flange 14 of which one edge of the belt 10 travels. The edge of the belt 10 adjacent the branch conveyers travels over the flange 15 of a suitably supported angle bar 16. The side wall 13 is made in sections which also act as side walls for the branch conveyers B and C (see Fig. 1).

The branch conveyers B and C are similar in construction and differ from each other 80 merely by reason of the fact that they are intended to handle boxes of different sizes. Each branch conveyer embodies a belt section, a movable section and an inclined section. The belt section includes a traveling 85 belt 20 which passes over end rollers 21 and 22, idler rollers 23 and a tension roll 24. The edges of the belt rest upon and travel along the flanges of angle bars 25 suitably supported below the side walls 13. The forward end roller 21 of each branch conveyer is mounted upon a shaft 26 driven from a motor 27 through a flexible coupling 28 and a gear reduction mechanism 29 so that the travel of the belts 20 in both branch conveyers is at a uniform rate.

The movable conveyer section 30 comprises a plurality of rotatably supported rollers 31 carried by flange side bars 32. The bars 32 are suitably connected and pivotally 100

mounted upon stud shafts 33 at their forward ends and rest upon cams 34 carried by a shaft 35. The shaft 35 is preferably made in two sections connected by a universal 5 joint 36 and is driven from the conveyer roller 22 in the following manner. Mounted upon one end of the shaft 37 which carries the roller 22 of branch conveyer B is a pinion 38 which meshes with a gear wheel 10 39 fixed at one end of a shaft 40 suitably supported in the frame below and parallel to the shaft 37, and having at its other end a pulley 41 which, through a belt 42, drives a pulley 43 mounted on the end of the shaft 15 35. It will be noted that while the shaft 35 is made in two sections the connection 36 insures their uniform rotation. The cams 34 are so positioned upon the shaft 35 that when the movable section 30 of either conveyer 20 is raised on its pivotal connection, the movable section of the other conveyer is lowered. Thus, the positions shown in Figs. 2 and 4 take place simultaneously. Interposed between the movable section 30 and 25 the belt section is a stop 45 formed by one end of a strap 46. The other end 47 of the strap is fixed upon a rock shaft 48 mounted in bearings 49 carried by the frame 50 on which the section 30 is supported. The shaft 30 48 is preferably rectangular in cross section except at the ends where it is cylindrical and is supported in the bearings 49. The end 47 of the strap 46 may be bent around the rectangular section of the shaft 48 and secured 35 by a set screw 51. The shaft 48 is rocked by and in unison with the movable section by an arm 52 fixed at one end to the shaft and having at its other end a slot 53 which receives the end of a cross rod 54 40 carried by the side rails 32.

The boxes are fed onto the movable section 30 by an inclined section 60. This section preferably acts through the force of gravity to advance the boxes and may be of any desired type. As here shown the section 60 comprises suitably supported flanged rails 61 which carry freely rotatable rollers 62 and side rails 63. The sections 60 may be of any desired length and the boxes be delivered thereto in any well known manner. It will be apparent that when the movable section 30 is raised as shown in Fig. 4 the free end thereof will prevent the travel of any boxes from the section 60 and thus functions 45 as a stop. The movable section 30 is of such length that it will support at one time only one box.

The operation of the branch conveyers will now be described with particular reference 50 to Figs. 3 and 4 of the drawings wherein the movable section 30 and stop 45 of the branch conveyer C are shown in the two extreme positions which they are caused to occupy by the rotation of the shaft 35. As shown in 55 Fig. 3 when the section 30 is in the plane of

the belt 20 the stop 45 projects into the path of travel of the box 65 and holds it upon the section 30. As the shaft 35 is rotated, however, the cams 34 raise the section 30 on its pivot pins 33 and at the same time through 60 the action of the arm 52 and shaft 48 the stop 45 will be lowered so that the box 65 on the section 30 which has been checked by the stop 45 will now be released and allowed to slide onto the belt 20. The section 30 in 65 its raised position, (see Fig. 4) acts as a gravity conveyer and the box supported thereon advances without further attention to the belt 20. The free end of the movable section, however, extends into the way of any 70 boxes which may be passing down the inclined section 60 and stops their progress. When the section 30 returns to the Fig. 3 position, the boxes on the section 60 are then free to advance onto the section 30 until the 75 leading box comes into contact with the stop 45. The cams 34 controlling the section 30 of the branch conveyer B are arranged diametrically with respect to the cams 34 which control the section 30 of the conveyer C. As 80 a result, when the section 30 of one conveyer is raised and its box passed to the belt 20, the section 30 of the other conveyer is receiving its box and at the same time the stop 45 of the first conveyer will be inoperative to 85 permit the box to pass while the stop 45 of the other conveyer will be operative to check the box on the section 30.

One purpose of this invention is to provide 90 an article transporting conveyer to which articles may be supplied in convenient amounts with the assurance that they will be delivered at intervals either individually or in groups of any predetermined number. Thus the articles may be delivered onto the inclined section 95 60 but by the operation of the movable section 30 and the stop 45 they will be automatically separated and be delivered from the conveyer by the belt 20 at regularly spaced intervals. The broad advantages flowing 100 from this construction whereby a regular supply of articles of any size or dimensions is assured without the necessity of any handling after the articles are first fed into the conveyer are obvious and need not be particularly specified.

Another purpose of this construction resides in the feeding of the load units to the main conveyer A and in view of the construction just described it will be obvious that the units from each branch conveyer advance at 110 regular intervals to the main conveyer and consequently when delivered onto the main conveyer are at a predetermined distance apart. Furthermore it will be apparent that 115 when a unit is being fed by the belt 20 of one branch conveyer no unit is being delivered by the belt 20 of the other branch conveyer. The operation of these conveyers is so timed that each unit delivered by the sec- 120

ond acting branch conveyer enters the main conveyer at the space provided between the units delivered by the first acting branch conveyer, and there is no danger of any collision which would interfere in any way with the operation of the main conveyer.

While the conveyers of the illustrated embodiment are intended to handle boxes of different sizes it will be understood that this invention is not limited thereto and consequently in the claims the term load units has been employed to designate the articles delivered by the branch conveyers which articles may be supplied either singly or in groups.

It will be understood that the particular type of conveyers shown and described as A, B and C were merely selected for the purpose of illustration and that other types of conveyers could be substituted therefor without departing from the spirit and scope of the invention as set forth in the following claims.

We claim:

1. The combination with a main conveyer of a pair of branch conveyers by which load units are fed onto the main conveyer, means independent of the main conveyer for operating the branch conveyers and means actuated seriatim by said first named means for regulating the feeding operations of the branch conveyers which means includes a movable section of each branch conveyer, and means for shifting said sections alternately out of position and thereby stopping the feeding operations.

2. The combination with a main conveyer of a pair of branch conveyers by which load units are fed onto the main conveyer, means independent of the main conveyer for operating the branch conveyers and means actuated seriatim by said first named means for regulating the feeding operations of the branch conveyers which means includes a movable section of each branch conveyer, a movable stop associated with each section and means for shifting the section and stop of each conveyer concomitantly and alternately with the section and stop of the other conveyer.

3. The combination with a main conveyer of a pair of branch conveyers by which load units are fed onto the main conveyer, means independent of the main conveyer for operating the branch conveyers and means actuated seriatim by said first named means for regulating the feeding operations of the branch conveyers which means includes a movable stop associated with each conveyer and mechanism for shifting said stops concomitantly whereby when one stop is in the functioning position and holds a load unit stationary the other stop is in the idle position and permits a load unit to advance.

4. A conveyer comprising two aligned load unit transporting sections, means for operat-

ing one of said sections, a movable section interposed between the transporting sections, said movable section in one position being in alignment with said first-named sections to receive a load unit from one section and, in another position, being out of such alignment to deliver the received load unit to the other transporting section, and means actuated by said means for moving said movable section.

5. A conveyer comprising two aligned load unit transporting sections and a movable section interposed between the transporting sections, a movable stop associated with the movable section, means for actuating the stop and section so that in one position the movable section is in alignment with said first-named sections to receive a load unit from one transporting section and the stop checks the load unit on the movable section and, in another position, the stop is retracted and the movable section is out of such alignment to deliver the received load unit to the other transporting section, means for operating the transporting section to which the load unit is delivered and connections between said means and said stop and section actuating means by which said last named means is operated.

6. A conveyer comprising two aligned load unit transporting sections and a movable section interposed between the transporting sections, said movable section being, in one position, in alignment with said first-named sections to receive a load unit from one transporting section and, in another position, out of such alignment to deliver the received load unit to the other transporting section and to stop the travel of load units on the first transporting section, means for operating the transporting section to which the load unit is delivered, and means actuated by such operating means for moving said movable section.

7. A conveyer comprising two aligned load unit transporting sections and a movable section interposed between the transporting sections, a movable stop associated with the movable section, means for actuating said stop and section whereby the load units delivered by the first transporting section are individually stopped and delivered to the other transporting section a predetermined distance apart, means for operating the transporting section to which the load units are delivered and connections between said means and said stop and section actuating means by which said last-named means is operated.

8. A conveyer comprising two aligned load unit transporting sections and a movable section interposed between the transporting sections, the end of said movable section adjacent one transporting section being pivotally mounted and the other end adjacent the

other transporting section being free and means for raising and lowering the free end of the movable section so that in one position it will be in alignment with both transporting sections to receive load units from the second named transporting section and in another position will be out of such alignment to stop delivery of the load units thereto and deliver the load units thereon to the first-named transporting section, means for operating the transporting section to which the load units are delivered and connections between said means and said means for raising and lowering the movable sections by which said last-named means is actuated.

9. The combination with a main conveyer of at least two branch conveyers feeding thereto, each branch conveyer including a positively driven section by which the load units are delivered to the main conveyer, and a movable section which in one position delivers load units to the positively driven section, means for operating the positively driven sections of the branch conveyers continuously and means actuated by said means for moving the movable sections of the branch conveyers seriatim into the positions in which load units are delivered to the positively driven sections.

10. The combination with a main conveyer of at least two branch conveyers feeding thereto, each branch conveyer including a positively driven section by which the load units are delivered to the main conveyer, and a movable section which in one position delivers load units to the positively driven section, said movable section being adapted to be raised and lowered, means for operating the positively driven sections of the branch conveyers continuously and means actuated by said means for raising and lowering the movable sections of the branch conveyers seriatim so that each section in turn assumes the position in which load units are delivered to the positively driven section of the same branch conveyer.

11. The combination with a main conveyer of at least two branch conveyers feeding thereto, each branch conveyer including a positively driven section by which the load units are delivered to the main conveyer, and a movable section which in one position delivers load units to the positively driven section, said movable section being pivotally mounted and adapted to be raised and lowered, means for operating the positively driven sections of the branch conveyers continuously and means actuated by said means for raising and lowering the movable sections so that each section in turn assumes the position in which load units are delivered to the positively driven section of the same branch conveyer.

12. The combination with a main conveyer of at least two branch conveyers feeding

thereto, each branch conveyer including a positively driven section by which the load units are delivered to the main conveyer, and a movable section which in one position delivers load units to the positively driven section, said movable section being pivotally mounted at the end adjacent the positively driven section and being adapted to be raised into and lowered from the position in which it delivers load units to the positively driven section, means for operating the positively driven sections of the branch conveyers continuously and means actuated by said means for raising and lowering the movable sections seriatim so that each section in turn assumes the position in which load units are delivered to the positively driven section of the same branch conveyer.

Signed by HENRY C. KELLER at Syracuse, N. Y., this 7th day of April, 1930 and by MAYNARD VAN BILLIARD at Syracuse, N. Y., this 15th day of April, 1930.
